US00D958864S

(12) **United States Design Patent** (10) **Patent No.:** **US D958,864 S**
(45) **Date of Patent:** **** Jul. 26, 2022**

(54) **CAMERA**

(71) Applicant: **Cisco Technology, Inc.**, San Jose, CA (US)

(72) Inventors: **Shane Michael Costa Martins**, Moraga, CA (US); **Otto Williams**, Berkeley, CA (US); **Naoki Shimada**, Sunnyvale, CA (US)

(73) Assignee: **Cisco Technology, Inc.**, San Jose, CA (US)

(**) Term: **15 Years**

(21) Appl. No.: **29/761,146**

(22) Filed: **Dec. 7, 2020**

(51) LOC (13) Cl. **16-01**

(52) U.S. Cl.

USPC **D16/200**; D16/202

(58) **Field of Classification Search**

USPC D16/200-204, 207-208, 219, 218; D10/61, 63, 65, 70, 71, 104.1, 106.7; D14/203.1, 204, 209.1, 496, 497

CPC G03B 15/03; G03B 17/02; G03B 17/04; G03B 17/56; G03B 19/04; H04N 7/141; H04N 7/142; H04N 7/147; H04N 7/148; H04N 7/15; H04N 7/152; H04N 5/2251; H04N 5/2252; H04N 5/2253; H04N 5/2254; H04N 2101/00; H04N 2007/145

(57) **CLAIM**

The ornamental design for a camera, as shown and described.

DESCRIPTION

FIG. 1 is a top, front, right-side perspective view of a camera with a privacy shutter in an opened position;

FIG. 2 is a bottom, back, left-side perspective view thereof;

FIG. 3 is a front view thereof;

FIG. 4 is a back view thereof;

FIG. 5 is a right-side view thereof;

FIG. 6 is a left-side view thereof;

FIG. 7 is a top view thereof;

FIG. 8 is a bottom view thereof;

FIG. 9 is a top, front, right-side perspective view of the camera with the privacy shutter in a closed position; and,

FIG. 10 is a front view thereof.

(Continued)

The dashed broken lines depict portions of the camera that form no part of the claimed design.

1 Claim, 10 Drawing Sheets
